SANDER FOR LOCOMOTIVE VALVES

Edward R. Hauer, Lakewood, Ohio, and Edwin L. Cull, Chicago, Ill., assignors to Viloco Railway Equipment Co., Chicago, Ill., a corporation of Illinois

Application March 23, 1942, Serial No. 435,874

4 Claims. (Cl. 291—11)

The invention relates to sanding apparatus for locomotives.

Sander-traps used on locomotives are usually provided with a nozzle for discharging sand for delivering it to the track adjacent the driving wheels of the locomotive, and also with an orifice or nozzle for delivering a short blast of air for clearing the delivery pipe, as a part of each sanding operation. The air to the sander-traps is usually controlled by an operator's valve which is provided with a handle which can be set to control air both for the clean-out blast and the sand-trap. Usually the valve is adapted to control the clean-out blast when set in an intermediate position and by a continuing movement of the handle to a third position, to deliver air to the sand-discharge nozzle. In this practice, the engineer may manually hold the handle in its intermediate position for the desired short period necessary for the clean-out blast, and then shift the handle to its position for delivering air to the sand-discharge nozzle, where it is left until the sanding desired has been completed. In practice it has been found that the engineer at times will overlook the shift of the handle from clean-out to sanding position, which will result in an unnecessarily prolonged clean-out blast. In locomotive practice it is of great importance to conserve the air used for sanding because it is derived from a reservoir from which air is also used for the air-brake system of the train. If the clean-out blast is prolonged beyond the short period necessary, the discharge of air may reduce greatly the main reservoir pressure and bleed the train line of the entire train, which results in delays in restoring the air-brake system to operative condition. The prolonged clean-out blast may also tend to excessively discharge sand from the trap. It is desirable in present practice to conserve the sand supply for long runs of the locomotive.

One object of the invention is to provide sanding apparatus with time-controlled means for limiting the duration of the clean-out blast independently of the operator's valve so that in the event the engineer should fail to shift the valve handle from its clean-out position to the sanding position, the clean-out blast will be interrupted for the purpose of conserving the air supply.

Another object of the invention is to provide improved sanding mechanism for locomotives whereby only a blast of predetermined duration will be delivered by the clean-out nozzles.

Another object of the invention is to provide

improved means for preventing excessive use of air in sanding apparatus.

Other objects of the invention will appear from the detailed description.

5 The invention consists in the several novel features hereinafter set forth and more particularly described in the claims at the conclusion hereof.

In the drawing:

Fig. 1 is a diagrammatic view of sanding apparatus embodying the invention.

10 Fig. 2 is a section of the timing valve for controlling the duration of the clean-out blasts.

Fig. 3 is an elevation partly in section of the reservoir for air which is used to close the timing 15 valve.

Fig. 4 is a view of the operator's valve for controlling the sanding apparatus, the handle and head of the casing being removed.

Fig. 5 is a section of the sand-trap.

20 The invention is exemplified as used on a locomotive *a* which is provided with a series of sander-traps *b* to which sand is supplied by pipes *c*, respectively, and pipes *d* for delivering the sand discharged from one of the traps to the rail adjacent one of the drivers of the locomotive. Each trap *b* is provided with a suitable nozzle *e* for delivering air under pressure into its trap chamber for discharging sand, and an orifice *f* which functions as a nozzle for a clean-out blast across one end of the trap chamber and into a delivery pipe *d*. The trap may be of any suitable construction as well understood in the art.

An operator's valve *g*, located in the cab of the locomotive, comprises a casing *g¹* which is adapted to receive a supply of air from pipe *g²* which is connected to the main air reservoir on the locomotive. A handle or lever *g⁴* is adapted to rotate a valve disk *g⁵* to three positions for selectively cutting off the supply of air to the sand-traps, delivering blasts to the clean-out nozzles, and delivering air to the sand-delivering nozzles. Valve disk *g⁵* is provided with a pair of ports *g⁶*. The valve-seat in casing *g¹* is provided with a 35 pair of diametrically opposite cross-connected ports *g⁷* which communicate with a port to which a pipe *g⁸* is connected for the delivery of air to the clean-out nozzles. Casing *g¹* is also provided with a port *g⁹* which is adapted to receive air through one of the ports *g⁶* in disk *g⁵*. Port *g⁹* is connected to a pipe *g¹⁰* for the delivery of air to the sand-delivery nozzles *e* in the traps. Pipe *g¹⁰* may be connected by branches to the traps on 40 both sides of the locomotive. The handle *g⁴* is movable from a normal position in which the sup-

45 50 55

ply of air is cut off to pipes 10 and 11, to an intermediate position in which air will be delivered to pipe 10 for the clean-out nozzles f, and to a third position in which air will be delivered to the sand-delivery nozzles e of the traps and cut off air to clean-out nozzles f. Pipe 10 is connected by branch pipes 12 to the nozzles f, and may be connected by a branch to the sand-traps on both sides of the locomotive. Pipe 11 is connected by suitable branch pipes to the sand-delivery nozzles e in the traps b.

A timing valve 14 is included in the pipe 10 for controlling the flow of air from the valve g to the clean-out nozzles f in the traps. Valve 14 comprises a body 15 having an inlet cavity 16 to which the pipe 10 leading from valve g is connected, and an outlet cavity 17 from which the pipe 10 leads to the clean-out nozzles f. A valve-member 18 is slidably mounted in the casing 15 and is adapted to close against a seat 19 between cavities 16 and 17. A lower piston 23 on member 18 is slidable in a portion of the cylinder formed in the casing 15 and an upper piston 24 is slidable in the upper casing section 22. A diaphragm 21 is clamped between casing sections 15 and 22 and is held between pistons 23 and 24 to form a fluid tight joint between said casing sections. A nut 26 threaded to the stem 18^a of member 18 clamps the inner portion of diaphragm 21 between pistons 23 and 24. A shoulder 25 is engaged by piston 24 to limit the movement of the valve-member 18 away from its seat. A spring 27 between nut 26 and the upper portion of casing section 22 holds the valve member normally against its seat 19. A reservoir 30 is adapted to retain a predetermined volume of air under pressure corresponding to that deemed necessary for the clean-out blasts. This reservoir is closed and is connected by a pipe 31 to the upper end of casing section 22. A chamber 32 in casing section 22 has an opening 33 leading to a pipe 31. The stem 18^a of valve-member 18 is provided with a duct 34, the lower end of which connects with orifice 35 which extends through the closure 18 and connects with cross orifice 36 in the closure member which communicates with the inlet cavity 16 in the casing 15. Reservoir 30 is closed and provided with a plug 30^a for access to its interior. The reservoir 30 is usually secured by bolts 40 in a convenient location in the locomotive cab.

The operation of the apparatus will be as follows: Normally handle g⁴ of the operator's valve g will be positioned to close the ports in the casing g¹ leading to the pipes 10 and 11 so that the traps will be inoperative. In initiating a sanding operation the engineer will first shift handle g⁴ to the intermediate of its three positions. The ports g⁶ in disk g⁵ will then deliver air and establish communication through ports g⁷ to the pipe 10 which is connected to the timing valve 14. Air under pressure will flow into inlet cavity 16 of valve 14 and acting on the piston 23 will lift valve-member 18 against the force of spring 27. Air will then flow from the inlet cavity 16 to the outlet cavity 17 and thence to the clean-out nozzles through pipe 10 and branches 12. Air in restricted volume will flow through the cross port 36, ports 35 and 34 and through pipe 31 to the reservoir 30. As soon as sufficient pressure is built up in reservoir 30 to act with the force of spring 27 on the upper piston 24 and to overcome the air pressure against the under side of piston 23, member 18 will be shifted to its seat 19 and cut off the blast 75

to the clean-out nozzles. This will occur in the event that the engineer permits the handle g⁴ to remain in its intermediate position for supplying air to the clean-out nozzles, and times 5 and limits clean-out blasts. If the engineer does not delay shift of the handle g⁴ to its third position, valve disk g⁵ will admit air from casing g¹ through port g⁹ to pipe 11, for the operation of the sand-discharge nozzles as long as desired, and as the valve disk g⁵ is shifted to the 10 third position the supply of air to pipe 10 and timing valve 14 will be cut off. The air in reservoir 30 and the pipe 10 will then leak through ports 35, 36, the pipe 10, and the clean-out nozzles to atmosphere, so the timing valve 14 will 15 close in readiness for a succeeding sanding operation. If during the return movement of the handle g⁴ to its normal position the engineer should stop it at its intermediate position, the 20 timing valve 14 will operate in like manner as before described to cut off the supply of air from the operating valve to the clean-out nozzles. When operator's valve g is closed after the completion of the sanding operation, air 25 from reservoir 30, if it has been filled, and from the portion of the pipe 10 between valves 14 and g, will escape through ports 34 and 35 while the valve-member 18 is closed, at a small rate to the clean-out nozzles. The ports 36 and 35 are 30 so small that if the air thereto is not cut off at valve g, the leakage of air from inlet cavity 16, while valve 14 is closed will be insignificant.

The invention exemplifies sanding apparatus in which clean-out blasts are used for clearing 35 the sand-delivery traps and air for discharging the sand from the traps is used, a device included for timing or limiting the clean-out blast when the engineer fails to do so. The air reservoir having a limited capacity serves as simple 40 means for timing the valve and limiting the duration of the clean-out blasts.

The invention is not to be understood as restricted to the details set forth since these may be modified within the scope of the appended 45 claims without departing from the spirit and scope of the invention.

Having thus described the invention, what we regard as new and desire to claim by Letters Patent is:

- 50 1. In sanding apparatus for locomotives the combination with a sand trap provided with a clean-out nozzle for clearing the sand delivery pipe and an air nozzle for discharging sand from the trap, an operator's valve and pipe connections for separately conducting air from the operator's valve to the clean-out nozzle and to the sand discharge nozzle, said valve being provided with means for manually and successively controlling the separate delivery of air to the pipe connection for the clean-out blast and air to the sand discharge connection for a sanding operation, and for controlling air to the pipe connection for the clean-out blast when the valve is shifted from sanding to its closed position, 60 of an automatic time-controlled valve for air included in the pipe connection leading to the clean-out nozzle connection, for cutting off the clean-out blasts at the end of a predetermined period during the shift of the control means from closed to sanding position and from sanding position to closed position, said valve being provided with a restricted passage for air to the clean-out nozzle and which remains open when said latter valve is closed.
- 65 2. In sanding apparatus for locomotives the

combination with a sand trap provided with a clean-out nozzle for clearing the sand delivery pipe and an air nozzle for discharging sand from the trap, an operator's valve and pipe connections for separately conducting air from the operator's valve to the clean-out nozzle and to the sand discharge nozzle, said valve being provided with means for manually and successively controlling the separate delivery of air to the pipe connection for the clean-out blast and air to the sand discharge connection for a sanding operation, of automatic time-controlled means for cutting off the clean-out blasts at the end of a predetermined period comprising a valve provided with a casing included in the pipe connection between the operator's valve and the clean-out nozzle and a reservoir for air separate from the valve casing and connected to receive air from the pipe-connection for the clean-out nozzle said valve being provided with a restricted passage for air to the clean-out nozzle from the reservoir which remains open when said latter valve is closed.

3. In sanding apparatus for locomotives the combination with a sand trap provided with a clean-out nozzle for clearing the sand delivery pipe and an air nozzle for discharging sand from the trap, an operator's valve and pipe connections for separately conducting air from the operator's valve to the clean-out nozzle and to the sand discharge nozzle, said valve being provided with means for manually and successively controlling the separate delivery of air to the pipe connections for a sanding operation, of automatic time-controlled means for cutting off the clean-out blasts at the end of a predetermined period comprising a valve provided

with a casing included in the pipe connection between the operator's valve and the clean-out nozzle and a reservoir for air separate from the valve casing and connected to receive air from the pipe-connection for the clean-out nozzle, said valve being provided with means for discharging accumulated air from the reservoir into the pipe-connection for and to the clean-out nozzle when said latter valve is closed.

5 4. In sanding apparatus for locomotives the combination with a plurality of sand traps, each having a sand delivery pipe connected thereto and provided with a clean-out nozzle for clearing the sand delivery pipe and an air nozzle for discharging sand from the trap to the delivery pipe, an operator's valve, a pipe for separately conducting air from the operator's valve connected to deliver air to the clean-out nozzles in the plurality of traps, a pipe for separately conducting air from the operator's valve to the sand discharge nozzles, said valve being provided with means for manually and successively controlling the separate delivery of air to said pipes, and means comprising a reservoir and a single time-controlled valve included in the pipe for delivering air to the clean-out nozzles for cutting off the clean-out blasts to the plurality of traps at the end of a predetermined period, said latter valve being provided with a passage for discharging accumulated air from the reservoir into the pipe connection for and to the clean-out nozzle when said latter valve is closed and with a port for delivering air to the reservoir from the operator's valve while air is flowing to the clean-out nozzles.
